UNITED STATES PATENT OFFICE.

RANDOLPH CROMPTON AND HORACE WYMAN, OF WORCESTER, MASSACHUSETTS, ASSIGNORS TO THE CROMPTON & KNOWLES LOOM WORKS, OF SAME PLACE AND PROVIDENCE, RHODE ISLAND.

LOOM.

SPECIFICATION forming part of Letters Patent No. 600,488, dated March 8, 1898.

Application filed November 27, 1896. Serial No. 613,579. (No model.)

To all whom it may concern:

Be it known that we, RANDOLPH CROMPTON and HORACE WYMAN, of Worcester, county of Worcester, State of Massachusetts, have 5 invented an Improvement in Looms, of which the following description, in connection with the accompanying drawings, is a specification, like letters and figures on the drawings representing like parts.

10 This invention has for its object the production of a loom in which, when the filling is broken or exhausted from the shuttle, that shuttle will be ejected and a new or spare shuttle supplied with filling will be automatically substituted for it.

15 In our improved loom one end of the lay carries and has movably mounted upon it a sliding shuttle-box, which we shall designate as the "running" shuttle-box, and coöperating with the said running shuttle-box we employ an auxiliary shuttle-presenter, it normally standing still and containing a spare shuttle provided with filling, the end of the filling on the shuttle in the auxiliary shuttle-presenter being connected with a suitable filling-holder.

20 When the filling in the shuttle, which is thrown pick after pick from the running shuttle, is broken or exhausted, the auxiliary shuttle-presenter, which is unattached to the running shuttle-box and which, while the shuttle in the running shuttle-box is being thrown pick by pick, is locked or held in its inoperative position, is released to come into 25 position under the running shuttle-box, and thereafter the auxiliary shuttle-presenter is moved to put it into its temporary operative position, the running shuttle-box being displaced, so that the shuttle in the auxiliary 30 shuttle-presenter may be thrown therefrom across the lay. Prior, however, to throwing the shuttle from the auxiliary shuttle-presenter across the lay the shuttle having the broken filling is returned into the running 35 shuttle-box, so that when the latter is put into its inoperative position and the auxiliary shuttle-presenter into its operative position the exhausted shuttle then in the running shuttle-box in inoperative position may be

extracted or taken from said running shuttle-box automatically.

The running shuttle-box, it having a binder at one side, is slotted at its rear side for the entrance of a picker which is made movable in usual manner on a picker-guide rod, and 55 the auxiliary shuttle-presenter, it also having a binder, has at its rear side a slot for the entrance of the picker, so that when the auxiliary shuttle-presenter is put into its operative position opposite the level of the race 60 of the lay the picker referred to may enter said presenter and throw the shuttle across the lay.

The picker has operatively connected with it an ejector which, as the picker is retracted, 65 engages the spent shuttle in the running shuttle-box then in its inoperative or abnormal position and withdraws the said spent shuttle from said shuttle-box, so that as soon as the spare shuttle in the auxiliary shuttle-presenter has been thrown across the lay through the shed the running shuttle-box 70 may descend into its operative position at the level of the race of the lay to receive said spare shuttle on its return flight, it being 75 thereafter thrown from said running shuttle-box until the thread in it is exhausted, when the same operation referred to again takes place.

The auxiliary shuttle-presenter detached 80 from the running shuttle-box is herein shown as provided with a shuttle-box rod, which, through a suitable lever actuated, it may be, by any usual shuttle-box-lever-actuating devices, may be raised and lowered at the proper 85 and desired times, and, as herein shown, the movements of the pattern-chain controlling the shuttle-box mechanism are determined through the movement of the filling-fork. At that pick at which the spare shuttle is 90 thrown across the lay the movement of the take-up may be stopped. In other words, it will be seen herein that the so-called "running" shuttle-box is movably mounted on and travels with the lay in its to-and-fro movements and that said shuttle-box normally stands in such position on said lay that the shuttle carried by it may be thrown there- 95

from across the lay so long as the filling is unbroken, but that said box is free to be put into its inoperative or abnormal position when the filling breaks, it being put into such inoperative position, however, only after the breaking of the filling, detected in usual manner, as by a filling-fork, and the shuttle with the broken filling has been returned into the said running box. The running shuttle-box, having received the spent shuttle, is put into its inoperative position, as stated, and the auxiliary shuttle-presenter normally unattached to and disconnected from the running box and whose sole function is simply to supply the raceway of the loom with the spare or fresh shuttle for the one in which the filling has just been exhausted is released from its normal inoperative position and is put temporarily into operative position at the race of the lay, it having combined with it, for the purpose of so moving it from its inoperative into its operative position, suitable actuating mechanism, it remaining in its operative position at the level of the race of the lay only long enough to enable the spare shuttle contained in the auxiliary shuttle-presenter to be thrown across the loom, said shuttle on its return stroke entering the running shuttle-box, it having had the spent shuttle extracted from it and having returned into its operative position at the level of the race of the lay.

We believe ourselves to be the first in a loom to employ with a lay having a running shuttle-box, which travels with and partakes of the motions of the lay, an auxiliary unattached shuttle-presenter which during the regular operations of the loom is held in a stationary or inoperative position, so that it may be easily provided with a spare shuttle, said unattached shuttle-presenter being put into its operative position in place of the running shuttle contained in the running shuttle-box; or, in other words, we have, as we may say, divided a multicelled shuttle-box into two parts, leaving each part capable of being put into operative position opposite the level of the race of the lay, so that a shuttle in each of said boxes may be thrown therefrom across said lay, and we have provided means to hold one of these boxes, which for the sake of clearness in the description of operation we have called the "unattached" shuttle-presenter, in its inoperative position, except at a pick following the exhaustion or breaking of a thread in the running shuttle-box, the said unattached shuttle-presenter being then put into operative position with relation to the lay, so that the picker will take from it its spare shuttle having a fresh supply of filling, the said unattached shuttle-presenter, deprived of its spare shuttle, being immediately put again into its inoperative position, where it may be again supplied with a spare shuttle without stopping the loom.

Figure 1 in front elevation, broken out cen-

trally, however, represents a sufficient portion of a well-known loom with our improvements added to enable our invention to be understood. Fig. 2 is a detail to be referred to. Fig. 3 is a left-hand end view of the loom shown in Fig. 1. Fig. 3^a is a detail of the shuttle-box-lever-actuating crank-shaft. Fig. 3^b shows the gear on said shaft. Fig. 4 is an enlarged rear side elevation of one end of the lay and the running shuttle-box and the auxiliary shuttle-presenter, the running shuttle-box being elevated preparatory to ejecting the spent shuttle from it. Fig. 5 is a top view of Fig. 4. Fig. 6 shows the rear side of the shuttle. Figs. 7 to 12, inclusive, show different sectional views of the lay and of the running shuttle-box and auxiliary presenter in positions which they assume in one round of operations.

A is the loom-frame; A', the breast-beam; A², the lay; A³, the lay-connecting rods; A⁴, the crank-shaft; A⁵, the rock-shaft, on which are mounted the lower ends of the lay-sword; A⁶ and A⁶ is the lower or cam shaft, which derives its motion from a toothed gear thereon, which is actuated by a toothed gear on the crank-shaft, said gears being shown simply by dotted circles, the crank-shaft having two rotations to one of the cam-shaft.

The cam-shaft has fast on it a cam a, which during each rotation acts upon the long arm of a hammer-lever a', pivoted at a², the upper end of said lever engaging the tail of the weft-fork a³, pivoted at a⁴ on the weft-fork slide a⁵, which when the weft fails to tilt the fork a³ and lift its tail out of the path of movement of the weft-hammer is caught by the said hammer, thus moving the slide in the guideway a⁶, secured to the top of the breast-beam.

a⁶X represents a rock-shaft mounted in suitable bearings of stands a⁷, the said rock-shaft having at one end an arm a⁸, having a bent end which engages the weft-fork slide, the opposite end of the rock-shaft having an arm a⁹, the said arm being raised whenever the weft-fork slide is moved outwardly by reason of the absence or failure of the weft.

The end of the lay has suitable guideways e, in which, as herein shown, are placed the ends of the main or running shuttle-box e', it being loosely placed in said guides and movable therein, so that the shuttle may be thrown across the lay, the direction of movement of the running shuttle-box being herein represented as vertical.

The running shuttle-box, normally, when not acted upon by the auxiliary shuttle-presenter, obeying the action of gravity, has a binder e², which is acted upon by a spring e³, and it has a lug e⁴, which, when said running shuttle-box is in its operative position at the level of the race of the lay, meets and is supported by the bar e⁵ carried by the lay, where it may stand in its operative position, it, as herein shown, being retained by the said lug meeting a shoulder e⁶, connected with the lay. The running shuttle-box has also at its rear

side a slot e^6 . The lay between the said guides e has a slot e^7 , coinciding with the slot e^6 , the picker e^8 , mounted to slide on the rod e^9 , entering the said slots e^7 e^6 when operating to 5 throw the shuttle e^{10} , which in this description we shall designate as the "running" shuttle, it being provided with filling.

The object of this invention is to replace automatically the running shuttle e^{10} by another shuttle, which we shall call an "auxiliary" or "spare" shuttle, when the filling breaks or becomes exhausted from the running shuttle.

The rock-shaft A^5 , constituting the fulcrum for the lay, has loose upon it at one end outside the loom side the hollow feet of a stand c , having suitable openings or bearings c^1 for the reception of a rod c^2 , provided at its upper end with an auxiliary shuttle- 15 presenter c^3 , said shuttle-presenter normally holding in it an auxiliary shuttle e^4 , said shuttle-presenter being capable of being moved to and fro about a center which is substantially the center of motion of the lay.

20 The lower end of the rod c^2 enters a collar c^5 , having a pin c^6 , the pin receiving over it a link c^7 , attached to a lever c^8 , pivoted at c^9 , the opposite end of the lever c^8 , which we shall hereinafter designate as the "shuttle-box" lever, having jointed to it a link c^{10} , which embraces a crank-pin c^{12} on a disk c^{14} on the shuttle-box-lever-actuating crank-shaft c^{13} , having its bearings c^{15} fixed to the framework. This shaft c^{13} has fast on it a 25 toothed gear d^8 , having two of its teeth removed at substantially diametrically opposite points, (see Fig. 3^b), the said gear being grooved where the said teeth are omitted. The groove receives the ends of two prongs

30 of a sliding fork d^{10} , having two teeth d^{13} , which when the arms of the said fork are inserted into the said groove far enough to put the teeth d^{13} into line with the remaining teeth of the gear d^8 , make of it a full gear, 35 which will be engaged and rotated by the toothed sections d^1 d^2 of the mutilated gear d fast on the lower or cam shaft A^6 . The sliding fork has at its outer end an annular groove d^{14} , which is entered by a pin at one end of 40 an elbow-lever d^{15} , pivoted on a stud d^{16} , extended from a stand d^{17} , the opposite end of said lever having attached to it a link d^5 , attached to an arm g^{17} of a rock-shaft g^{15} , having its bearings in a stand g^{16} , the opposite 45 end of said rock-shaft having a second arm g^{18} , to which is connected the rod g^{14} , attached to the finger g^{10} , which is acted upon by the pattern surface or cam g^9 of a shaft g^8 , said pattern surface or cam having a series of projections 50 7 and spaces 8, so as to lift the finger g^{10} and then lower it alternately in regular order when said cam is moved, it being understood that when the loom is running regularly the finger will rest on a space, but when 55 the weft fails the cam will be moved to cause a projection to lift the finger and move the forked gear into position to put its two

teeth in line with the teeth of the gear d , so that one of the two sets of teeth d^1 or d^2 , whichever first arrives, will engage one of 70 said teeth and rotate the said gear and shaft one-half a rotation and then leave it at rest momentarily, and then the second set of teeth d^1 or d^2 will come into position and further rotate the said shaft to complete a full rotation thereof, after which the cam will be again moved and let the finger g^{10} drop and move the forked gear into its inoperative position, leaving the crank-pin up. It is while the said crank is down at the completion of the 80 first-half rotation of said shaft that the auxiliary shuttle, having a full supply of weft, is thrown from the auxiliary shuttle-presenter through the shed across the lay.

The auxiliary shuttle-presenter has suitable 85 ears to receive a rod h^{13} , on which are mounted the ears of a plate or binder h^{12} , provided with a face or block of leather or other friction material b^2 to bear on the auxiliary or spare shuttle e^4 ; a spring b^3 surrounding said rod 90 and normally keeping the said plate or binder closed, as in Figs. 9 and 10. This auxiliary shuttle-presenter is normally held stationary in front of the lay, and it is entirely independent and detached from the running shuttle-box and the lay and is provided with a 95 spare shuttle, which is placed in position by hand to be taken by the said presenter and put in position at the race of the lay to be thrown onto said race. As herein shown, 100 when the said auxiliary or spare shuttle is placed in position to be taken by the presenter the plate or binder h^{12} , which may be located at one side of the presenter, but which is normally closed by a spring, may be 105 turned down, said spring acting normally to keep the shuttle in place on the lay in line with the picker traveling on the guide-rod of the lay, so that said shuttle may be started from the same point at which the shuttle 110 which was used in the running shuttle-box started in its flight across the lay. The plate or binder h^{12} , which may be attached to the said shuttle-presenter, is shown as having attached to it a suitable filling end holder h^{14} , 115 shown as a projection about which the free end of the filling on the bobbin the auxiliary shuttle will be wound.

The auxiliary shuttle-presenter has at its inner side a slot 2, which receives the picker 120 when the latter is acting to throw the auxiliary shuttle from said shuttle-presenter. The collar c^5 is secured to the lower end of the rod by means of suitable check-nuts 3, and to insure the retention of the shuttle-presenter 125 in the proper straight line the rod c^2 is provided with a collar having a forked guide 4, which embraces the stand c as the rod c^2 is reciprocated.

The rod c^2 has fast on it a collar b^5 , having 130 at its inner side a projection b^6 , (shown by full lines, Figs. 1 and 4, and by dotted lines, Fig. 3,) which is engaged by a suitable catch or holder b^7 , shown as a notched arm ex-

tended from a rock-shaft b^8 , said catch engaging the projection b^6 and holding the auxiliary shuttle-presenter in its inoperative position, Fig. 3, when the loom is running 5 regularly. The rock-shaft b^8 has a second arm b^9 , which is bent inwardly over the loom side and crosses the arm a^9 before described.

The hubs at the lower ends of the stand c embrace loosely the rock-shaft A^6 , and one of 10 said hubs has an arm b^{12} , to which is attached a tension-spring b^{13} , connected to a stationary ear b^{14} of the loom side.

So long as the running shuttle supplies the filling properly the catch b^7 retains the auxiliary shuttle-presenter in its normal or inoperative position represented in the drawings; but as soon as the filling fails and the filling-fork slide is moved outwardly across the breast-beam the arm a^9 in rising acts on 15 the arm b^9 and lifts the catch quickly, thus freeing the rod c^2 and letting the spring b^{13} throw the auxiliary shuttle-presenter against the lay, and thereafter the auxiliary shuttle-presenter partakes of the backward-and-forward 20 movement of the lay, while the auxiliary shuttle-presenter is actuated to perform its work, as will be described, after which it is again caught by the hook b^7 and held in its 25 normal position, as will be described.

30 The arm a^9 has connected to it a link g , attached to the end of a lever g' , pivoted at 6 on a stand at the loom side, said lever at its opposite end having connected with it a rod g^2 , which is attached to a pawl-controller g^8 , 35 pivoted at g^4 and provided with a toe g^5 , a suitable spring g^{60} (see Fig. 3) normally acting on the lever g' to keep the said toe elevated and form a rest for a pawl f^6 , mounted on an elbow-lever B , pivoted at B^2 , said lever 40 having connected with it a rod g^6 , which in practice will be moved constantly from the lower cam-shaft, as provided for in United States Patent No. 364,696, dated June 14, 1887, the said pawl when permitted to drop into engagement with the teeth of a ratchet-wheel or cam g^7 , fast on said pattern-shaft g^8 , causing a projection thereon to act upon and raise the finger g^{10} , pivoted at g^{12} . In practice the cam will be so shaped as to present alternately 45 a high part, as a roll or projection 7 and a space 8. Whenever the finger g^{10} is lifted by a projection, the shaft c^{18} will be rotated for one hundred and eighty degrees, as will be described, to first pull down the inner end 50 of the box-lever c^8 and thereby raise the rod c^2 of the auxiliary shuttle-presenter, and immediately thereafter, the shuttle having been thrown from the auxiliary presenter, the said shaft will have given to it a movement through 55 one hundred and eighty degrees, which will lower the said auxiliary shuttle-presenter, after which the pattern-surface will be moved another step by the pawl f^6 to let the finger g^{10} drop and leave the crank up and shuttlebox-lever c^8 in its normal position, with the 60 box-rod down until again to be called into operation after the failure of the filling. When 65

the filling is exhausted or at fault in the running shuttle, the raising of the arm a^9 , before described, pulls down on the rod g^2 and lowers 70 the controller g^8 , letting the pawl f^6 engage the ratchet-wheel g^7 and turn the pattern-surface two steps, one immediately after the other. As the finger g^{10} is lifted by the cam the rod g^{14} , connected therewith, is raised. 75 The rod g^{14} has pivoted upon it a weighted or counterbalanced catch f , which when the rod is lifted passes but without moving a toe f' on a short rock-shaft f^2 , having an attached second arm f^3 , to which is connected a rod 80 f^4 , attached at its opposite end to a dog f^5 (shown by dotted lines, Fig. 3) and pivoted at 15, said dog being weighted at f^7 , so that whenever the arm a^9 is raised it will fall under a pin 10, extended therefrom, and keep 85 the said arm elevated and the controller g^8 in position to enable the pawl f^6 to work twice in succession. At proper times, however, the auxiliary shuttle-presenter having effected its purpose, (to be described,) the pattern surface is moved, letting the rod g^{14} drop, and then the counterbalanced catch f strikes the toe f' , pulls the dog f^5 , and releases the arm a^9 , so that the catch b^7 may drop into operative position and be again in place to engage 95 the auxiliary shuttle-presenter.

The lay has attached to one of its swords a stud n , which serves as the fulcrum of the restoring device or lever n' , provided at its lower end with a link n^2 , jointed to a stud n^3 100 of the stand b^{14} , so that the upper end of said lever is moved backward and forward with the lay, it passing forward as the lay goes forward. The upper end of this lever n has a projection n^4 , which as the lay is moved forward after the auxiliary shuttle-presenter has been lifted meets the projection b^6 and pushes the box-rod c^3 forward toward the breast-beam, so that the projection b^5 will be in position to be engaged by the catch b^7 when it descends, said catch descending immediately 110 after the rod g^{14} descends, as it does at the second movement of the pattern-cam, for then the balanced dog f by its action pulls back the weighted dog f^5 to release the arm a^9 . 115

The picker-stick D , of usual construction and retracted by any usual spring or device D' , enters a hole (see Fig. 5) in the picker e^8 , and surrounding the rod e^9 and embracing the picker is a slide or catch D^2 , having a 120 vertical stud or finger D^3 , upon which is mounted an extractor D^4 , shown as a pivoted lever having an inturned end and acted upon by a spring 12. (See Fig. 5.) This extractor partakes of the movement of the picker. 125

The shuttles used in this loom have at their rear side a notch D^5 , (see Fig. 6,) preferably surrounded by a metallic plate D^6 , the said notch being entered by the hook of the extractor when the shuttle is to be extracted 130 from the running shuttle-box, as will be described.

In operation let it be assumed that the running box is provided with a shuttle having

filling which is being properly laid into the shed and that the auxiliary shuttle-presenter is locked in its normal position by the hook b^7 , as represented in Fig. 3. Now should the filling fail the filling-fork will not be tipped, and consequently its tail will be caught by the hammer, which will cause the filling-fork slide to be moved and effect the partial rotation of the rod a^{6x} , lifting its arm a^9 and letting the dog f^5 fall under the pin 10. The raising of this arm a^9 to act of the arm b^9 raises the hook b^7 and immediately frees the auxiliary shuttle-presenter, letting the spring b^{13} throw it to the left from the position Figs. 3 and 7 to meet the lay, as in Fig. 8, and this same movement of the arm a^9 , acting through the lever g^9 and rod g^2 , lets the pawl f^6 come into operation to move the pattern surface or cam and effect the lifting of the finger g^{10} , that movement throwing into operative position the sliding fork, causing its teeth to be put in line with the continuously-rotating teeth d^1 and d^2 of the partial gear d , and the crank-shaft c^{13} will be quickly rotated by one section of said teeth for half a rotation; but just before this half-rotation takes place the running shuttle has come back again into the running shuttle-box, as represented in Fig. 9. The first half of the rotation of the crank-shaft c^{13} quickly lifts the auxiliary shuttle-presenter from the position Fig. 9 into the position Fig. 10 and lifts in advance of it the running shuttle-box, as represented in Fig. 10, and the said running shuttle-box and shuttle-presenter remain in that position until the picker-stick in its forward movement causes the picker to act on the auxiliary shuttle marked c^1 and throw it from the auxiliary shuttle-presenter through the shed into the empty box at the opposite end of the lay, and as the picker is moved backwardly the ejector D^4 , acted upon by the spring 12, enters the slot e^7 in the back of the running shuttle-box, engages the notch D^5 , and withdraws the exhausted or spent shuttle from the running shuttle-box, and, as herein shown, before the shuttle thrown from the auxiliary shuttle-presenter has an opportunity to return again the second half-rotation of the crank-shaft c^{13} takes place, pulling down the auxiliary shuttle-presenter from its position opposite the level of the race of the lay and putting the running box in the position opposite the level of the race of the lay, so that it may receive on its return stroke the shuttle previously thrown from the auxiliary shuttle-presenter, and this done the pattern-surface is again moved, letting the finger g^{10} drop, which effects the withdrawing of the sliding fork and the removal of its teeth from the teeth of the gear d^8 , which leaves the auxiliary shuttle-presenter down, and the said shuttle-presenter is moved forward by the restoring-lever n' with the lay as it beats in the filling, and the hook b^7 , released by the descent of the rod g^{14} with the finger g^{10} , as described, presents the projection b^6 in position to be engaged and

held by the catch b^7 to keep the auxiliary shuttle-box again in its normal position. The spent shuttle, which is drawn from the end 70 of the running shuttle-box, in this instance of this invention, drops on the floor, or it may drop into any suitable receptacle placed at the end of the lay to receive it. A spring 16, surrounding the rock-shaft b^8 , acts normally 75 to depress the hook b^7 and keep the arm b^9 against arm a^9 , the rock-shaft being held in a suitable stand 17.

The devices herein shown for moving the shuttle-box lever are substantially the same 80 as represented in United States Patent No. 260,349, dated June 27, 1882, and instead of the particular devices shown we may employ any other usual or well-known shuttle-box-lever-moving mechanism. 85

The disk c^{14} is acted upon by a suitable brake o' , controlled by a spring o^2 , the brake preventing the overrunning of the shaft c^{13} , all as well known and common in looms.

Having described our invention, what we 90 claim as new, and desire to secure by Letters Patent, is—

1. In a loom the following instrumentalities, viz: a lay; a running shuttle-box carried permanently thereby and capable of movement thereon temporarily from its operative position in line with the race of the lay into its inoperative position out of line with the race of the lay; an independent auxiliary shuttle-presenter normally disconnected from said 95 running shuttle-box and held stationary with relation to said moving lay during the regular running of the loom, and means on the failure of the filling in the shuttle of the running box to move said shuttle-presenter from its stationary inoperative position into its operative position at the lay, the position occupied by the running shuttle-box when the filling failed, substantially as described. 100

2. In a loom, the following instrumentalities, viz: a lay; a running shuttle-box carried permanently thereby and capable of movement thereon from its operative position in line with the race of the lay into its inoperative position out of line with the race of the 115 lay; an independent auxiliary shuttle-presenter containing a spare shuttle and held stationary at or near the breast-beam in its inoperative position during the regular operations of the loom; and means on the absence 120 of the filling from the shuttle in the running shuttle-box to move said shuttle-presenter from its inoperative position at the breast-beam toward the advancing lay through a 125 path at an angle to the movement of the running shuttle-box on the lay, said shuttle-presenter coming into its operative position at the level of the race of the lay, the position previously occupied by the running shuttle-box, and means to insure the movement of 130 the shuttle-presenter into its inoperative position with relation to the lay during its next forward stroke, substantially as described.

3. In a loom the following instrumentalities,

ties, viz: a lay; a running shuttle-box carried thereby and having a movement thereon from its operative into its inoperative position; an auxiliary shuttle-presenter normally held in its inoperative position at rest while the lay is moving in the regular working of the loom, and pivotally mounted below the level of the race of the lay; means on the failure of the filling in the running shuttle-box to move the said auxiliary shuttle-presenter from its inoperative position toward and to meet the advancing lay, said shuttle-presenter coming into its operative position at the race of the lay in place of the running shuttle-box; and means to insure the movement of the auxiliary shuttle-presenter in unison with the lay until the spare shuttle has been thrown from the said presenter onto the race of the lay, substantially as described.

4. In a loom the following instrumentalities, viz: a lay; a running shuttle-box carried thereby and having a movement thereon from its operative into its inoperative position; an auxiliary shuttle-presenter normally held in its inoperative position at rest while the lay is moving in the regular working of the loom and pivotally mounted below the level of the race of the lay; means on the failure of the filling in the running shuttle-box to move the said auxiliary shuttle-presenter from its inoperative position into its operative position at the race of the lay, in place of the running shuttle-box; and means to insure the movement of the auxiliary shuttle-presenter in unison with the lay until the spare shuttle has been thrown from the said presenter onto the race of the lay, and means to again return the said auxiliary shuttle-presenter to its inoperative stationary position, as the lay, having been supplied with a spare shuttle from said shuttle-presenter, next comes forward toward the lay, substantially as described.

5. In a loom the following instrumentalities, viz: a lay; a running shuttle-box carried thereby and having a movement thereon from its operative position in line with the race of the lay into its inoperative position out of line with said race; an independent unattached auxiliary shuttle-presenter provided with an auxiliary or spare shuttle; holding means to retain said shuttle-presenter in its inoperative stationary position during the regular operations of the loom, devices to move said holding means to release said auxiliary shuttle-presenter on the failure of the filling in the running shuttle-box, and means to put the said auxiliary shuttle-presenter in its operative position at the level of the race of the lay and cause it to move with the lay while the spare shuttle is thrown from the auxiliary shuttle-presenter onto the race of the lay, substantially as described.

6. In a loom the following instrumentalities, viz: a lay; a running shuttle-box carried permanently thereby and capable of movement thereon temporarily from its operative position in line with the race of the lay into its

inoperative position out of line with the race of the lay, and having a binder; an independent auxiliary shuttle-presenter normally disconnected from said running shuttle-box and held stationary with relation to said moving lay during the regular running of the loom; and means on the failure of the filling in the shuttle of the running box to move said shuttle-presenter from its stationary inoperative position toward the advancing lay into its operative position, the position occupied by the running shuttle-box when the filling failed, substantially as described.

7. In a loom the following instrumentalities, viz: a lay; a running shuttle-box carried permanently thereby and capable of movement thereon temporarily from its operative position in line with the race of the lay into its inoperative position out of line with the race of the lay; an independent auxiliary shuttle-presenter normally disconnected from said running shuttle-box and held stationary with relation to said moving lay during the regular running of the loom, a rod attached to said presenter, a lever to which said rod is connected, and devices to actuate said lever to place said presenter in its operative position at the level of the race of the lay in place of the running shuttle-box, and at the same time place the running shuttle-box temporarily in its inoperative position out of line with the race of the lay, substantially as described.

8. In a loom the following instrumentalities, viz: a lay; a running shuttle-box carried permanently thereby and capable of movement thereon temporarily from its operative position in line with the race of the lay into its inoperative position out of line with the race of the lay; an independent auxiliary shuttle-presenter normally disconnected from said running shuttle-box and held stationary with relation to said moving lay during the regular running of the loom, a box rod or carrier for said presenter, a lever to which said rod or carrier is connected, a filling-fork, and means set in motion by the movement of said fork due to absence of filling in the running shuttle-box to start and move said lever and shuttle-presenter from its inoperative stationary position into its operative position at the level of the race of the lay, and at the same time place the running shuttle-box in its inoperative position, said shuttle-presenter moving with the lay while the spare shuttle thereon is thrown onto the race of the lay, and devices to retain the said auxiliary shuttle-presenter in its stationary inoperative position as the lay next comes forward with said shuttle-presenter after the spare shuttle has been thrown from it onto the lay, substantially as described.

9. In a loom the following instrumentalities, viz: a lay; a running shuttle-box carried thereby and having a vertical movement thereon from its normally operative into its inoperative position with relation to the race

of the lay on the failure of the filling; an auxiliary shuttle-presenter detached from said running shuttle-box and not partaking of the movements of the lay during the regular operation of the loom, and normally occupying its inoperative position near the breast-beam; a rod or carrier attached to said presenter; a lever having a fulcrum independent of and stationary with relation to the lay; and devices on the failure of the filling to actuate said lever and place the said presenter in its operative position at the level of the race of the lay, the running shuttle-box being put at such time in its inoperative position, substantially as described.

10. In a loom, the following instrumentalities, viz: a lay, a running shuttle-box carried and normally sustained in its operative position at the level of the race of the lay, an auxiliary shuttle-presenter, a box-rod to which it is attached, a movable stand to guide said box-rod, holding means to normally hold said box-rod with the shuttle-presenter in its inoperative position, a filling-fork, and means 25 actuated thereby when the filling is absent to move said holding means and effect the release of said auxiliary shuttle-presenter, and devices to place said auxiliary shuttle-presenter in its operative position, the position 30 previously occupied by said running shuttle-box, substantially as described.

11. In a loom, the following instrumentalities, viz: a lay, a running shuttle-box carried and normally sustained in its operative position at the level of the race of the lay; an auxiliary shuttle-presenter provided with a spare shuttle and normally stationary in its inoperative position near the breast-beam while the lay is moving during the regular operation 35 of the loom, a box-rod connected to said auxiliary shuttle-presenter to support it, a normally stationary box-rod guide, means to move said auxiliary shuttle-presenter when the filling fails to thereby put the auxiliary 40 shuttle-presenter with its spare shuttle at the level of the race of the lay in place of the running shuttle-box, said shuttle-presenter moving with the lay until its shuttle is thrown therefrom through the shed; substantially as 45 described.

12. In a loom, the following instrumentalities, viz: a lay, a running shuttle-box carried and normally sustained in its operative position at the level of the race of the lay, an auxiliary shuttle-presenter, a rod attached thereto, a movable stand to guide said rod, a spring 55 to move said stand in one direction, holding means to normally hold said auxiliary shuttle-presenter in its inoperative position against the stress of said spring, a filling-fork, and means actuated thereby when the filling is absent to move said holding device and effect the release of said auxiliary shuttle-presenter that it may meet and be moved in unison with 60 the lay, and devices to place said auxiliary shuttle-presenter in its operative position, the

position previously occupied by said running shuttle-box, substantially as described.

13. A lay provided with a loosely-mounted running shuttle-box, an auxiliary shuttle-presenter independent of the lay and adapted to hold a spare shuttle, said shuttle-presenter having a plate to act against the outer side of a spare shuttle, combined with devices to move said auxiliary shuttle-presenter from its 75 normally stationary and inoperative position with relation to the lay, into its operative position at the level of the race of the lay, in place of said running shuttle-box, said auxiliary shuttle-presenter being retained in its operative position, while the shuttle is thrown across the race of the lay, and means to then again return said auxiliary shuttle-presenter into its inoperative position that it may remain stationary as the lay moves in the regular operation 80 of the loom, substantially as described.

14. In a loom, the following instrumentalities, viz: a lay; a running shuttle-box, an auxiliary shuttle-presenter, its rod having a projection, a pivoted guide in which the said 85 rod may slide, holding means to engage said projection, and hold said shuttle-presenter stationary in its inoperative position, substantially as described.

15. In a loom, the following instrumentalities, viz: a running shuttle-box, an auxiliary shuttle-presenter, its rod having a projection, a pivoted guide in which said rod may slide, holding means to engage said projection, means to cause said holding means to remain 90 in engagement with said projection and hold said shuttle-presenter stationary in its inoperative position, a filling-fork, and means under the control of said fork to operate said holding means and release said projection, and 95 means to turn said guide and with it the shuttle-presenter and its rod toward the lay, to operate, substantially as described.

16. In a loom, a lay, a running shuttle-box permanently carried thereby, an auxiliary 100 shuttle-presenter having a rod provided with a projection, a spring-controlled catch co-operating with said projection, means to move the lay to and fro with relation to said auxiliary shuttle-presenter, means to actuate said 105 spring-controlled catch to release it from said projection and let the auxiliary shuttle-presenter be moved temporarily with the lay, and means to again effect the engagement of said spring-controlled catch with said projection 110 to again lock the auxiliary shuttle-presenter in a stationary inoperative position, substantially as described.

17. In a loom, the following instrumentalities, viz: a lay, a running shuttle-box loosely 115 mounted on and carried by the lay, an auxiliary shuttle-presenter, a catch to hold said shuttle-presenter in its normal or inoperative position, means to move said catch to release said auxiliary shuttle-presenter and let it be 120 moved toward the lay on the failure of the filling, and an arresting device or lever to re- 130

turn said auxiliary shuttle-presenter again into its normal inoperative position after the shuttle carried by it has been delivered into the shed, substantially as described.

5 18. In a loom, a lay, a running shuttle-box mounted on and movable with it to and fro, a pivoted stand having its fulcrum substantially at the fulcrum of the lay, an auxiliary shuttle-presenter having its rod mounted in 10 said stand, a catch to engage and hold said auxiliary shuttle-presenter in its normal or inoperative position, means to release said catch on the failure of the filling, a spring to move the said stand, the shuttle-box rod and 15 the auxiliary shuttle-presenter when released by said catch to let said shuttle-presenter meet the lay, substantially as described.

19. In a loom, the following instrumentalities, viz: a lay, a running shuttle-box carried 20 permanently thereby and vertically movable thereon, an auxiliary shuttle-presenter independent of and unattached to the running shuttle-box, and normally occupying its inoperative position near the breast-beam 25 out of the range of movement of the lay; a filling-fork, and means controlled thereby on the failure of the filling in the shuttle in the running shuttle-box to quickly move said auxiliary shuttle-presenter toward the advancing 30 lay into position below the running shuttle-box and to lift said presenter and shuttle-box; said presenter following with the lay on its back stroke, and means to act on the auxiliary shuttle in said shuttle-presenter and 35 throw said shuttle across the lay, substantially as described.

20. In a loom, the following instrumentalities, viz: a lay, a picker-guiding rod carried by it, a picker on said rod, a running shuttle-box mounted on and carried by the lay and 40 provided with a binder, and slotted at its rear side for the entrance of the picker, means to determine the descent of said running shuttle-box and place it in position so 45 that the shuttle carried by it will be at the level of the raceway of the lay; an independent auxiliary shuttle-presenter provided at its rear side with a picker-receiving slot, and carrying a spare shuttle; a holding device to 50 maintain said auxiliary shuttle-presenter in its inoperative position so long as the filling of the shuttle in the running shuttle-box is unbroken; a filling-fork, means actuated by it to move the said holding device and release 55 the auxiliary shuttle-presenter when the filling breaks or is exhausted from the running shuttle-box; and means to thereafter place the auxiliary shuttle-presenter with its shuttle at the level of the race of the lay to be 60 thrown therefrom across the lay by the picker, the putting of the auxiliary shuttle-presenter into its operative position serving to put the running shuttle-box with its spent shuttle, for one pick, into its inoperative position, 65 substantially as described.

21. In a loom, the following instrumentalities, viz: a lay, a picker-guiding rod carried

by it, a picker on said rod, a running shuttle-box mounted on and carried by the lay and provided with a binder and slotted at its rear side for the entrance of the picker; means to determine the descent of said running shuttle-box and place it in position so that the shuttle carried by it will be at the level of the raceway of the lay; an independent auxiliary shuttle-presenter provided at its rear side with a picker-receiving slot and carrying a spare shuttle; a holding device to maintain said auxiliary shuttle-presenter in its inoperative position so long as the filling of the shuttle in the running shuttle-box is unbroken; a filling-fork, means actuated by it to move the said holding device and release the auxiliary shuttle-presenter when the filling breaks or is exhausted from the running shuttle-box; and means to thereafter actuate the auxiliary shuttle-presenter with its shuttle at the level of the race of the lay to be thrown therefrom across the lay by the picker, the putting of the auxiliary shuttle-presenter into its operative position serving to put the running shuttle-box with its spent shuttle, for one pick, into its inoperative position, and an extractor to extract the said spent shuttle from the said running shuttle-box when in its inoperative position, substantially as described.

22. In a loom, the rock-shaft a^{6x} and its arm a^9 having a pin; the dog f^5 , its attached rod f^4 , and rock-shaft having an arm f^3 and toe f^1 ; combined with a rod g^{14} having a counterbalanced dog, and a pattern-surface to move the latter rod, and actuate the dog f^5 to release the arm a^9 , substantially as described.

23. In a loom, the following instrumentalities, viz: a lay, a running shuttle-box carried thereby, it normally occupying a position at the level of the race of the lay, an unattached auxiliary shuttle-presenter disconnected from said lay and having a spare shuttle and held normally in its inoperative position below the level of the race of the lay, means on the failure of the filling to put said presenter under the running shuttle-box and lift said presenter into its operative position at the level of the race of the lay, the lifting of said presenter putting the running shuttle-box into its inoperative position, and means to retain said presenter at the level of the race of the lay until after the said spare shuttle has been thrown from said auxiliary shuttle-presenter, and means to thereafter place said presenter again in its inoperative position, and the running shuttle-box into its operative position to receive, on its return, the shuttle just thrown from the said auxiliary shuttle-presenter across the lay, substantially as described.

24. In a loom, the following instrumentalities, viz: a lay, operating means therefor, a running shuttle-box movable with the lay, an auxiliary shuttle-presenter containing a spare shuttle and normally occupying a position stationary out of line with the level of the race of the lay, means to hold said auxiliary

- shuttle-presenter stationary while the filling in the shuttle being thrown from the running box is unbroken, means to operate said holding means when the filling is to be changed
- 5 to let the said auxiliary shuttle-presenter move toward and meet the running lay, means to thereafter move said auxiliary shuttle-presenter and put the spare shuttle contained in it at the level of the race of the lay,
- 10 means to throw the spare shuttle from said auxiliary shuttle-presenter across the lay, and to then move said auxiliary shuttle-presenter out of line with the race of the lay and place the same in position to be again engaged by
- 15 the holding means, so that it may be locked in stationary position, where said auxiliary shuttle-presenter may again be supplied with a spare shuttle, substantially as described.
25. In a loom, the following instrumentalities, viz: a lay, a running shuttle-box carried thereby and having a movement thereon from its operative into its inoperative position, an independent unattached auxiliary shuttle-presenter disconnected from said lay
- 25 and provided with a spare shuttle, means to normally retain said shuttle-presenter in its inoperative position with relation to the lay, a filling-fork, and means controlled as to its time of operation by or through the said filling-fork when the filling fails, to put said auxiliary shuttle-presenter in its operative position at the race of the lay in place of the said running shuttle - box, substantially as described.
- 35 26. In a loom, the following instrumentalities, viz: a lay, a running shuttle-box carried thereby and normally occupying a position in line with the race of the lay, an independent unattached auxiliary shuttle - presenter provided with a spare shuttle, holding means independent of said lay to normally hold said shuttle-presenter stationary in its inoperative position near the breast-beam, a filling-fork, and means between it and said holding means to actuate said holding means at the proper time to release the said shuttle-presenter, and means to thereafter actuate said shuttle-presenter and place it for one pick in its operative position at the race of the lay
- 50 in place of the said running shuttle-box, substantially as described.
27. In a loom, the following instrumentalities, viz: a lay; a running shuttle-box carried permanently thereby and capable of movement thereon temporarily from its operative position in line with the race of the lay into its inoperative position out of line with the race of the lay; an independent auxiliary shuttle-presenter normally disconnected from
- 55 said running shuttle-box and stationary with relation to said moving lay during the regular running of the loom, means to move said presenter to meet the moving lay, and to put the
- 65 said auxiliary presenter into its operative position at the level of the race of the lay until the shuttle carried by said presenter is thrown onto the lay, substantially as described.
28. In a loom, the following instrumentalities, viz: a lay; a running shuttle-box carried permanently thereby and capable of movement thereon temporarily from its operative position in line with the race of the lay into its inoperative position out of line with the race of the lay; an independent auxiliary shuttle-presenter normally disconnected from 70 said running shuttle-box and stationary with relation to said moving lay during the regular running of the loom; a rod attached to said presenter; shifting mechanism to put the said presenter into its operative position at and to move with the lay, until the shuttle carried by said presenter has been thrown onto the lay, and means to thereafter, at a subsequent forward beat of the lay, put said auxiliary presenter again in its inoperative position, 75 substantially as described.
29. In a loom, the following instrumentalities, viz: a lay; a running shuttle-box, mounted on and movable with said lay from its operative into its inoperative position and vice 80 versa, an auxiliary shuttle-presenter having its pivotal point substantially at the fulerum of the lay, and means to maintain said auxiliary presenter in its stationary inoperative position during the regular running of the 85 loom, and means on the failure of the filling in said running box to place the said auxiliary presenter with its shuttle in its operative position at the level of the race of the lay instead of the said running shuttle-box, substantially as described.
30. In a loom the following instrumentalities, viz: a lay; a running shuttle-box carried permanently thereby and capable of movement thereon temporarily from its operative 90 position in line with the race of the lay into its inoperative position out of line with the race of the lay; an independent auxiliary shuttle-presenter normally disconnected from said running shuttle-box and held stationary 95 with relation to said moving lay during the regular running of the loom, and means when the shuttle in said running box is to be changed, to put said auxiliary shuttle-presenter with its shuttle temporarily at the level 100 of the race of the lay, and put said running shuttle-box temporarily in its inoperative position, substantially as described.
